Primary Examiner — Michael A. Pratt

(74) Attorney, Agent, or Firm — Cahn & Samuels, LLP

(57) **CLAIM**

The ornamental design for a gel confectionery plunger dispenser, as shown and described.

DESCRIPTION

1. Gel confectionery plunger dispenser

1.1 : Perspective

1.2 : Top

1.3 : Bottom

1.4 : Front

1.5 : Back

1.6 : Right

1.7 : Left

1.8 : Exploded

A tubular liquid/gel container with finger grip at one end and an axially projecting depressible plunger extending from that container end for squirting gel confectionery from the container through a conical dispensing nozzle/tip at the opposite end.

1 Claim, 8 Drawing Sheets
